UNITED STATES PATENT OFFICE.

MARY ANNA BARTELS, OF WATCHUNG, NEW JERSEY.

METHOD FOR FORMING TIPS OF SHOE-LACES.

No. 925,266.

Specification of Letters Patent. Patented June 15, 1909.

Application filed July 8, 1908. Serial No. 442,474.

To all whom it may concern:

Be it known that I, MARY ANNA BARTELS, a citizen of the United States, and a resident of Watchung, in the county of Somerset and State of New Jersey, have invented a new and Improved Method for Forming Tips of Shoe-Laces, of which the following is a full, clear, and exact description.

The object of the invention is to provide a new and improved method for forming tips of shoe laces, in a very simple and economical manner and with a view to render the tip permanent, without the use of metallic stiffening, and to allow of giving the tip the same color as that of the body of the shoe lace.

The method consists essentially in applying an adhesive and stiffening mixture to the end of a shoe lace of a textile fabric, and then rolling the end into a tip and allowing the mixture to set and harden.

A practical embodiment of the invention is represented in the accompanying drawings forming a part of this specification, in which similar characters of reference indicate corresponding parts in all the views.

Figure 1 is a plan view of a shoe lace fabric on which the tip is to be formed; Fig. 2 is a similar view of the same and showing the adhesive and stiffening mixture applied to one end of the fabric; and Fig. 3 is a plan view of the shoe lace and its tip at one end.

In order to carry the above-described method into effect, use is made of an adhesive and stiffening mixture, a coating A of which is applied in a plastic or a paste-like state to one end B' of a shoe lace B made of a textile fabric, such as cotton, silk, mohair, wool or the like, and the said adhesive and stiffening mixture is formed of ingredients which when applied to the flat end B' fills the meshes thereof and also permeates the fibers of the fabric material, and when the saturated and coated end is subsequently rolled into a tip, then the overlying convolutions are caused to firmly adhere one to the other, to render the tip permanent, and when the mixture finally sets and hardens then the desired stiffness is given to the tip.

A very serviceable plastic mixture or paste having the several properties above-mentioned, can be formed by evaporating an ordinary shellac solution or brown japan until it becomes sufficiently thick and very

adhesive, and to this mass is then added a pigment to match the color of the fabric material B. Two parts of litharge, one part of bronze powder and twenty parts of shellac form the paste, which is applied to say about a half inch of the shoe lace at each end and at both sides. The lace end thus treated is then immediately rolled by hand or suitable machinery into conical shape, with a fine point at the end, as plainly indicated in Fig. 3. Another mixture which also gives good results, is formed of one part of plaster of paris, two-tenths part of shellac, five parts of corn starch, and zinc white in sufficient quantity and color to give a uniform color to the mixture.

In practice, the mixture is applied with a putty knife or a similar tool, but it is evident that suitable machinery may be employed for carrying out both the applying and rolling operation.

From the foregoing, it will be seen that the tip is formed by a cold process, in a very simple manner, and producing a tip which is exceedingly durable, moisture-proof and of a color corresponding to that of the fabric material of which the shoe lace is made.

Having thus described my invention, I claim as new and desire to secure by Letters Patent:

1. The herein described method for forming tips on shoe laces, consisting in saturating the fibers and filling the meshes of the end of a textile fabric shoe lace with a mixture of shellac and litharge, and then rolling the said end into a conical shape with a fine point at the end.

2. The herein described method for forming tips on shoe laces, consisting in saturating the fibers and filling the meshes of the flat end of a textile fabric shoe lace with an adhesive and stiffening mixture, consisting of evaporated shellac, a pigment and litharge, and finally rolling the said end into conical shape and allowing the mixture to set and harden.

In testimony whereof I have signed my name to this specification in the presence of two subscribing witnesses.

MARY ANNA BARTELS.
